Primary Examiner — Karen S Acker(74) *Attorney, Agent, or Firm* — Lee & Hayes, P.C.(57) **CLAIM**

The ornamental design for a vehicle seat, as shown and described.

DESCRIPTION

FIG. 1 is a top perspective view of a vehicle seat;

FIG. 2 is a bottom perspective view thereof;

FIG. 3 is a front view thereof;

FIG. 4 is a back view thereof;

FIG. 5 is a right-side view thereof;

FIG. 6 is a left-side view thereof;

FIG. 7 is a top view thereof; and,

FIG. 8 is a bottom view thereof.

The broken lines and unshaded areas within the broken lines and the unshaded areas adjacent to continuous solid lines depict portions of the vehicle seat that form no part of the claimed design.

1 Claim, 8 Drawing Sheets(56)
